UNITED STATES PATENT OFFICE.

WILLIAM J. McGAW, OF BEACHHAVEN, NEW JERSEY.

SHIRT-CUFF.

1,291,970.

Specification of Letters Patent. Patented Jan. 21, 1919.

Application filed October 18, 1917. Serial No. 197,204.

To all whom it may concern:

Be it known that I, WILLIAM J. McGAW, a citizen of the United States, residing at Beachhaven, in the county of Ocean, State 5 of New Jersey, have invented a new and useful Shirt-Cuff, of which the following is a specification.

My invention relates to an improvement in a cuff for a shirt of the kind that is fixed to the wrist band portion of the shirt sleeve in contradistinction to a cuff that is detachable from a wrist band, said wrist band portion having therein a buttonhole, or a number of such holes, and intermediate of said portion 10 and the cuff a transversely-extending seam whereby in the event of the fixed cuff having been worn away it may be severed from the wrist band portion leaving the latter and said seam intact and comprising in 15 effect a hem for the cut edge hem of the remaining former fixed cuff, thus providing a finish for the remaining wrist portion and serving to prevent raveling of the fabric at the cut edge thereof, while said portion is 20 adapted to have a removable cuff buttoned thereon.

The invention is satisfactorily illustrated in the accompanying drawing, but the important instrumentalities thereof may be varied, and so it is to be understood that the invention is not limited to the specific details shown and described, as long as they 30 are within the spirit or scope of the claim.

Figure 1 represents a plan view opened 35 out of a fixed cuff and a wrist portion thereof of embodying my invention.

Fig. 2 represents a perspective view of a 40 detachable cuff that may be used in lieu of the fixed cuff shown in Fig. 1.

Fig. 3 represents a perspective view of the 45 members shown in Fig. 1 in operative condition.

Fig. 4 represents a perspective view of the 50 wrist portion shown in Fig. 1, from which the fixed cuff has been removed.

Similar numerals of reference indicate 55 corresponding parts in the figures.

Referring to the drawings:—

1 designates a shirt cuff and 2 the wrist 60 band portion thereof to which the former is attached, as in the case of a soft fixed cuff, said wrist band portion extending from the portion 3 of a shirt sleeve, and said cuff being provided with holes 4 for the insertion 65 of a cuff button, said cuff being adapted to be folded on the line 5, all as well known.

The wrist band portion 2 is provided with holes 6 for buttoning purposes as will be hereinafter more fully described.

At about the place of junction of the cuff 60 1 and wrist portion 2 are the seams 7 which are sewed or stitched through the fabric at said place, thus uniting the plies thereof. It will be seen that when the cuff 1 wears away which is generally at the fold line 5, 65 it is not customary to replace it, hence it is lost and with it the shirt. In this case I cut off the cuff from the wrist band portion on the line 8 drawn through the cuff parallel with said seams at or near the wrist 70 band portion 2 and so the cuff may be thrown away, but the wrist band portion is comparatively intact and remains on the sleeve, while the cut edge 9 of the wrist band portion has adjacent to it in said portion the 75 seams 7 which comprise a sufficient finish to said wrist band portion and a guard or reinforce for said cut edge limiting also almost entirely the unraveling of the latter.

A practical wrist band 10 now presents it- 80 self and a separate or detached soft cuff 11 may be connected therewith, a form of the same being shown in Fig. 2, it being foldable on a line the same as 5 and provided with cuff buttonholes 12, and other buttonholes 85 13 and 14 for connection with buttons placed in the holes 6 of said wrist band, using either the side buttonholes 13 or the central button-hole 14, it being evident that if desired a separate or detached linen cuff may be connected with the wrist band 10, the same as the soft cuff 11.

It will be noted that the outer portion of the cuff 1 is of a length approximately the same as the combined length of the inner 95 portion and the wristband so as to practically overlap and cover, and so conceal the latter when the cuff is folded thereon.

Attention is directed to the fact that the band 2 is a conventional wristband proper 100 of the shirt, it being stitched to the sleeve and provided with buttonholes for the attachment of the separate cuff 11, Fig. 2, after the foldable cuff 1 primarily integral with said wristband is severed from the latter along the seam 7 intermediate of said wrist band and the inner member of the folded soft cuff 1. This then leaves said wrist band a complete member of the shirt as such, but in the manufacture of the said 110 soft cuff the outer fold thereof is of greater length than the inner fold thereof so that

when the cuff is folded on the line 5, which is out of center of the complete cuff, said outer fold not only covers said inner fold, but the entire wristband 2, and conceals the latter while the buttonholes 4 of both inner and outer folds are so spaced relatively to each other that when the cuff is folded on said line 5, said buttonholes 4 are in register for the insertion of the cuff buttons as employed for holding the two folds together folded on said line, it being apparent on reference to Fig. 1 that the three members, viz., the outer fold, the inner fold, and the wristband are respectively of different lengths so that while the outer fold covers the inner fold, it covers also the wristband, as shown in Fig. 3.

I am aware that a foldable soft turn over cuff has been made of two parts of equal length with a reinforcing strip on the fold line to strengthen the same. If a portion of said cuff is to be cut off it would leave the inner fold of the cuff of such length that it would extend far beyond the front edge of the coat sleeve, a matter of discomfort in wear against the hand, and not intended as a previously established wrist band of the sleeve of the shirt, as a third member thereof of considering the equal-length folds of the cuff as two members, this being a different

device from mine, and never intended for my purpose, hence I have made an improvement in the art.

Having thus described my invention what I claim as new and desire to secure by Letters Patent, is:—

A shirt sleeve having thereon a well-defined wrist band, the same being provided with holes for a cuff button for attachment of a separate cuff, and a cuff formed of outer and inner members foldable on each other integral and continuous outwardly from said wrist band, the outer member, the inner member, and said wrist band being of different lengths whereby the outer member when folded covers both the inner member and said wrist band, said outer and inner members having therein respectively button-holes adapted to register, the device having therein a seam intermediate of the inner fold of the cuff and the wristband whereby the cuff may be removed as an entirety by severing along the line of said seam leaving a practically finished outer edge to the remaining wristband for the purpose set forth.

WILLIAM J. McGAW.
